G. H. Corliss,

Steam-Boiler Water-Heater.

No 36,281.

Patented Aug. 26, 1862.

Augustus Dietrich
Esther S. Novot.

Geo. H. Corliss

UNITED STATES PATENT OFFICE.

GEORGE H. CORLISS, OF PROVIDENCE, RHODE ISLAND.

IMPROVEMENT IN STEAM-GENERATORS.

Specification forming part of Letters Patent No. 36,281, dated August 26, 1862.

To all whom it may concern:

Be it known that I, GEORGE H. CORLISS, of Providence, in the State of Rhode Island, have invented a new and useful Improvement in Steam Apparatus; and I do hereby declare the following to be a full and exact description thereof, reference being had to the accompanying drawings, and to the letters of reference marked thereon, in which—

Figure 1 is a sectional elevation of a steam-boiler with my improved apparatus attached. Fig. 2 is a plan or horizontal projection thereof. Fig. 3 is an end view of the same, and Fig. 4 shows a coil connected with a surface-condenser.

My invention is applicable to steam-boilers which are used in connection with surface-condensers, and embraces a steam-generator (shown at A) for the evaporation of salt or impure water, and which for this purpose is attached to the rear end of the boiler and is so constructed as to form a connecting-flue from the boiler to the chimney, and thus utilize the waste heat. This generator is connected with the surface-condenser by an open pipe, B, of sufficient area to give a free passage of the steam. The generator is therefore relieved of the pressure to which it would be subjected if

connected with the boiler, and in the position to which it is assigned is subjected to a comparatively low temperature, thus avoiding the formation of "scale."

A coil, C, Fig. 4, connected with the boiler by a pipe, D, is placed in the bottom of the generator, to increase the evaporation whenever the heat of the flue may be insufficient. The water formed within this coil is saved by being conducted to the surface-condenser by a pipe, E. At F a valve is shown for regulating the supply of water, and another valve at G for blowing off the saturated water.

What I claim as my invention, and desire to secure by Letters Patent of the United States, is—

1. A combination of a surface-condenser with a supplementary generator which takes its heat from the flue leading to the chimney, for the purpose set forth.
2. The combination of a surface-condenser, a supplementary generator, and coil of steam-pipe, substantially as and for the purpose described.

GEO. H. CORLISS.
